UNITED STATES PATENT OFFICE.

SAMUEL NORMAN CRAGIN, OF AKRON, OHIO.

FLOOR MOP.

Application filed August 11, 1927. Serial No. 212,304.

The object of my said invention is the provision of an efficient, durable and conveniently manipulated floor mop.

To the attainment of the foregoing the invention consists in the improvement as hereinafter described and definitely claimed.

In the accompanying drawings forming part of this specification:—

Figure 1 is a view illustrating my novel 10 mop in plan and with a portion of the mop body and the handle in section.

Figure 2 is a side elevation showing the preferred embodiment of my invention which has been reduced to practice and successfully used.

Figure 3 is a longitudinal section of the mop.

Similar numerals of reference designate corresponding parts in all the views of the 20 drawings.

As appears in Figures 2 and 3, the cloth 1 of the mop is in the form of a loop with closed ends, and both stretches or long portions of the mop are arranged at one side 25 of the mop body 2.

In the preferred embodiment of my invention the mop body 2 is made up of two major sections 3 and a minor interposed section 4, said sections being preferably, though 30 not necessarily, of wood. The sections alluded to are fixed together through the medium of bolts 5 and 6, and the bolt 5 which serves for the connection of the handle 7 is equipped with a nut 8 and is preferably removable. A portion of the handle 7 is interposed between the major sections 3 as clearly shown in Figures 1 and 3.

While I prefer for the sake of cheapness to form the body 2 of the sections connected 40 as described, it will be apparent that within the purview of my invention the body 2 may be formed in one piece of wood, metal or other appropriate material without affecting my invention.

At one end the body 2 is provided with longitudinal sockets 9, and in said sockets 9 are removably arranged the longitudinally disposed terminal portions of a wire loop 10 to which is secured the bight 11 at one 50 end of the mop cloth 1. At its opposite end which is bifurcated as designated by 12, the body is provided in the ends of the furcations 13 with kerfs or grooves 14. In the said kerfs or grooves 14 are removably seated the inwardly extending portions 15 on the wire loop 16 to which the opposite bight

17 of the mop cloth is secured as illustrated. The arms 15 are merged at their inner ends into longitudinal portions 18 disposed in the before mentioned bifurcation 12, and at 60 their inner ends said longitudinal portions 18 are merged into lateral arms 19 having enlargements 20 at their outer ends. Pivotally connected at 21 to the side edges of the body are keeper loops 22 which are designed to be swung on and off the enlargements 20 of the arms 19 of the loop 16.

It will be manifest from the foregoing that the wire loop 10 may be expeditiously and easily detached from and replaced in 70 engagement with the body 2 for the disconnection and the connection of the adjacent bight of the mop cloth 1 attached thereto. It will also be manifest that when the keeper loops 22 are swung laterally outward to 75 release the enlargements 20 of the wire loop 16, the said loop 16 or rather the portions 15 thereof may be displaced from the kerfs 14 to disconnect the bight 17 from the mop body. Manifestly when the portions 15 of 80 the wire loop 16 are replaced in the kerfs 14, and the keeper loops 22 are engaged with the enlargements 20, the wire loop 16 will be securely and strongly connected to the 85 mop body 2.

It will be appreciated from the foregoing that all the mop cloth 1 in my invention may be used for washing purposes, all of the cloth being between the body 2 and the floor and no portion of the cloth being off 90 the floor for the attachment of the mop to a handle for wringing purposes, or for any other purpose. On the other hand it will be manifest that when the loop 16 is disconnected from the body, the said loop without being removed from the cloth may be utilized as a handle for the wringing of the cloth after which the loop 16 may again be relatively arranged as shown in Figure 1 and connected to the body 2. I would further have it understood by virtue of the construction of my novel mop the mop is reversible. In order to reverse the mop it is simply necessary to remove the bolt 5 and the handle, and then remove the wire loop 100 16 and place the mop cloth at the opposite side of the body 2 and replace and connect the handle and the said wire loop 16.

It will further be appreciated that my novel mop provides for the expeditious replacing of a mop cloth when the same is worn out and that the mop is susceptible of 110

being used to advantage for waxing, washing, and polishing floors. Incident to the use of the mop no portion of wood or metal can strike and mar woodwork, all of the metal and wood being adequately covered by the mop cloth, which at all times is in interposed relation between the wood and metal portions of the mop and the floor and wainscoting. I would further have it understood that when the handle bolt 5 is tightened, the mop may be made to stand on edge against a wall so that no portion of the mop save the end of the mop cloth contacts with the floor.

In addition to the practical advantages hereinbefore ascribed to my novel mop it will be noted that the mop regardless of the position of the handle rests in the position shown in Figures 2 and 3, so that the mop cloth 1 is continuously stretched or maintained in a somewhat taut state. From this it follows that after use the mop cloth is adapted to quickly and thoroughly dry. Again, the handle 7 being swingable on the connecting bolt 5, either end of the mop may be inserted in a bucket for the wetting of the mop.

I have entered into a detailed description of the construction and relative arrangement of the parts embraced in the present and preferred embodiment of my invention in order to impart a full, clear, and exact understanding of the said embodiment. I do not desire, however, to be understood as limiting myself to the precise construction disclosed, my invention being defined by my appended claims within the scope of which modifications may be made without departure from my invention.

Having thus described the invention, what I claim as new and desire to secure by Letters Patent is:—

1. A mop comprising a body having longitudinally disposed sockets in one of its ends and also having its opposite end bifurcated and provided with kerfs in the ends of the furcations, a loop shaped mop cloth holder having longitudinally disposed terminal portions removably arranged in said sockets at one end of the body, a loop shaped mop cloth holder having portions removably arranged in the kerfs at the opposite ends of the body and also having longitudinally disposed portions and lateral arms at the inner ends of said portions and terminating in enlargements, and keeper loops pivotally connected to the side edges of the body and swingable into and out of engagement with said enlargements.

2. A mop comprising a body having longitudinally disposed sockets in one of its ends and also having its opposite end bifur-

cated and provided with kerfs in the ends of the furcations, a loop shaped mop cloth holder having longitudinally disposed terminal portions removably arranged in said sockets at one end of the body, a loop shaped mop cloth holder having portions removably arranged in the kerfs at the opposite ends of the body and also having longitudinally disposed portions and lateral arms at the inner ends of said portions and terminating in enlargements, and keeper loops pivotally connected to the side edges of the body and swingable into and out of engagement with said enlargements; the said bifurcation of the body receiving the end of a handle pivoted to the body, and the said handle being pivotally connected to the body through the medium of a removable pintle.

3. In a mop and in combination, a body, having a bifurcation in one end and also having kerfs in the ends of the furcations, keeper loops pivotally attached to the body at the side edges thereof, a mop cloth connected with one end of the body, and a loop engaging the mop cloth at the opposite end thereof, and having a pair of inwardly directed portions removably seated in said kerf and also having longitudinally disposed portions at the inner end of said inwardly directed portion and terminating at their rear ends in lateral portions which in turn terminate in enlargements arranged to be engaged by the said keeper loops.

4. In a mop and in combination, a body, bifurcated at one end and made up of spaced major sections, a section interposed between and connected to the major sections, the furcations of the body having kerfs in their ends, and the body being provided in its opposite end with longitudinally disposed sockets, a handle with one end arranged in the bifurcation in the body, a bolt removably secured in the body and pivotally connecting the handle to the body, a mop cloth having stretches or long portions and also having bights at its ends and joining said stretches or long portions, said mop cloth disposed at one side of said body, a loop disposed in one bight of the mop cloth and having longitudinal terminal portions disposed in said sockets of the body, keeper loops pivotally connected with the side edges of the body, and a loop disposed in the other bight of the mop cloth and having inwardly directed portions removably seated in said kerfs of the body and also having longitudinal portions and lateral portions extending from the inner ends of the longitudinal portions and terminating in enlargements adapted to be engaged by said loops.

In testimony whereof I affix my signature.
SAMUEL NORMAN CRAGIN.
